COMMODITY EXTRUDING COLLAPSIBLE
TUBE SUPPORTCarl F. Nelson, Mill Valley, and Verner A. Nelson,
Oakland, Calif.

Application September 27, 1947, Serial No. 776,594

4 Claims. (Cl. 222—103)

1

Our present invention relates to supporting devices and more particularly to a device for supporting a collapsible tube such as is commonly used for dispensing tooth paste, shaving creams, and the like.

An object of our invention is to provide a simple, inexpensive and practical supporting means by which a collapsible tube of tooth paste or like commodity may be mounted upon a wall where its contents may be extruded in a convenient manner without removal from the support.

Another object of the invention is to provide a new and novel form of support which may be attached to the wall of a washroom for holding a collapsible tube and in which a novel extruding mechanism is employed to extrude measured quantities of a commodity in a simple and effective manner.

Another object of the invention is to provide a collapsible tube discharging means upon a wall mounted support by which the contents of a collapsible tube may be extruded with a kneading action to thus insure against a caking or hardening of the contents of the tube at the closed end thereof.

We are aware that many attempts have been made to provide a practical support for tooth paste and like collapsible dispensing containers but so far as we are aware none of these devices have come into any extensive use. The need for such a device is generally due to a desire to have the particular commodity, whether it be tooth paste or shaving cream, in a convenient location where its contents may be extruded without entailing any messy operation or injury to the tube as so often happens when these tubes are rolled by hand. There is also the further difficulty that as these tubes become more collapsed and often distorted they require some special form of repository. In practice when squeezed by hand the contents of these tubes often become deposited on the outside of the tube and therefore the matter of placing them away in a medicine cabinet becomes objectionable and as a consequence these tubes in various degrees of discharge are more often found laying on the wash bowl where they present an untidy appearance. It is therefore a further object of our invention to provide a full and complete support for a collapsible tube commodity from which its contents may be extruded in a simple, convenient and neat manner and which will overcome the above objectionable features.

Other objects and advantages of our invention will be in part evident to those skilled in the

2

art and in part pointed out in connection with the accompanying drawing, wherein there is shown by way of illustration and not of limitation a preferred embodiment of the invention.

5 In the drawing;

Figure 1 is a front view of our improved device,
Figure 2 is a plan view of our device with the
base portion sectionalized along line II—II of
Figure 1,

10 Figure 3 is a vertical sectional view taken cen-
trally along line III—III of Figure 1 looking in
direction of arrows.

Figure 4 is a fragmentary sectional view similar
15 to Figure 3 showing the parts in another opera-
tive position, and

Figure 5 is a fragmentary view taken at the
bottom of Figure 1, showing the spring clip ar-
rangement employed for gripping the discharge
end of a collapsible tube.

20 Upon referring to the accompanying drawing it
will be noted that our improved collapsible tube
supporting device comprises two main cooperat-
ing portions; namely, a base or back portion 10
which is adapted to be hung upon a wall or other

25 suitable support and a vertically movable car-
riage 11 having means, as will be presently ex-
plained, by which the upper end of a commodity
dispensing collapsible tube 12 may be compressed.
As here shown the back or base portion 10 has
vertically extending side flanges 13 and 14 which
30 extend outwardly at the front thereof. Along the
inner surfaces of these vertically extending
flanges 13 and 14 there is a groove that forms un-
dercut trackways 15 into which outwardly dis-
posed lips 16 at each side of the movable carriage
35 11 extend. In this manner the carriage 11 is free
to move vertically along the base or back portion
10 when the latter is secured against a wall or
other surface. As a means for suspending the
base or back portion 10 upon a wall or other sur-
face there is a keyhole slot 17 through which a
40 nail or screw may extend. At its lower end the
base or back portion 10 has a horizontally dis-
posed and outwardly extending flange or boss 18
which carries a spring clip 19 that is adapted to
45 engage with the neck of the collapsible tube 12 be-
tween its shoulder 20 and a cap 21 at the end
thereof. At its other end, as is more clearly shown
in Figure 3 of the drawing, the collapsible tube 12
50 is gripped at its closed end between two eccentric-
ally mounted substantially cylindrical surfaces
22 and 23 which when rocked with respect to
each other will produce a squeezing or kneading
action alternately upon the opposite sides of
55 the tube 12. In this particular showing the ec-

centrically disposed cylindrical surfaces 22 and 23 are mounted between two side plates 24 and 25 which form a part of the movable carriage 11. In this instance the surface 22 is shown as formed by an arcuate member 26 which has end plates 27 that are pivotally mounted upon a transversely extending shaft 28 so that the upper portion of the arcuate member 26 may swing outwardly from the base or back portion 10 under the influence of a biasing spring 29 which is looped around the shaft 28. In order to limit this outward swinging movement of the arcuate members 26 there is provided oppositely disposed arcuate slots 30 in the side plates 24 and 25 of the movable carriage and into which the ends of a transversely extending pin 31 project. At this point it will be noted that the arcuate member 26 upon which the cylindrical surface 22 is formed is mounted closely adjacent the back or base portion 10 of the device and where it will be engaged by one side of the collapsible tube 12 when held by the neck engaging spring clip 19. In this position the arcuate member 26 with its cylindrical surface 22 will operate as a rocking anvil against which the collapsible tube 12 will be squeezed when the arcuate surface 23 is operated to extrude the contents of the tube 12. In this instance the arcuate surface 23 is shown as formed upon a lever-like member 32 which is pivotally mounted in spaced relation with the arcuate or anvil forming member 26 by means of a shaft 33 that extends through the side plates 24 and 25 of the carriage 11. This in effect forms what may be termed a cam-like hub portion upon the lever-like member 32 which will exert a rolling pressure upon the tube 12 when the lever-like member 32 is operated downward.

With the above arrangement and with particular reference to Figure 3 of the drawing it will be seen that when the collapsible tube 12 is engaged at its neck by the spring clip 19 and with its closed end disposed between the substantially cylindrical surfaces 22 and 23 formed respectively upon the arcuate member 26 and the lever 32, a downward movement of the lever 32 will cause the eccentrically disposed cylindrical surface 23 to roll downwardly in kneading fashion against the outside of the tube 12. At the same time the surface 22 upon the member 26 will yield with a somewhat contrary rolling action, as is more clearly illustrated in Figure 4 of the drawing, and as a result the contents of the tube 12 will be forced downwardly and extruded at the neck thereof. Under these conditions the cap 21 of the tube will be removed and by holding a tooth or shaving brush or the hand therebelow the extruded commodity may be conveniently collected. In this operation it will be understood that the amount of the commodity extruded during any one operation will be determined by the amount of movement imparted to the hand operated lever 32. Under normal operating conditions it is contemplated that only a very slight movement of the lever 32 will be found sufficient and as each desired quantity of the commodity is extruded the lever will be released and returned to its uppermost position. During this particular backward movement of the lever 32 the yieldingly supported anvil-like cylindrical surface 22 will again rock or swing outwardly against the tube 12 and cause the side of the tube 12 engaged thereby to be compressed a further amount to compensate for and equalize the deformation caused by the previous operation of the lever 32. Operating in this manner it will be seen that as the contents

of the collapsible tube 12 is discharged its closed or bottom end will become flattened. This will permit the movable carriage 11 to travel downwardly in the trackway 15 formed in the sides 14 of the back or base portion 10 until the tube 12 has become completely empty. An advantage of this arrangement is that by providing the rocking anvil-like surface 22 which engages one side of the tube 12 and the eccentrically mounted cylindrical surface 23 which engages the other side of the tube 12 there is effected a squeezing action that will be alternately applied to the opposite sides of the tube 12. In other words the contents of the tube may be said to be kneaded rather than squeezed out of the tube. Another advantage of this arrangement is that the contents of the tube will be more effectively extruded from the tube and with less danger of breaking the tube than is the case where the tube is compressed by two oppositely disposed rollers as has been proposed in many prior art devices produced for this purpose.

The particular device here described and illustrated in the accompanying drawing is constructed entirely of transparent plastic material which is cut, bent or rolled into the shapes desired from sheets and then cemented together by the use of a suitable adhesive. The spring 39 and the spring clip 19 are of course of spring steel. When constructed of this material in the manner shown the device with the tube 12 mounted therein presents a decidedly ornamental appearance which will further encourage its use in an exposed position upon the wall of a washroom.

While we have, for the sake of clearness and in order to disclose the invention so that the same can be readily understood, described and illustrated a specific form and arrangement, we desire to have it understood that this invention is not limited to the specific form disclosed, but may be embodied in other ways that will suggest themselves to persons skilled in the art. It is believed that this invention is new and all such changes as come within the scope of the appended claims are to be considered as part of this invention.

Having thus described our invention, what we claim and desire to secure by Letters Patent is—

1. In a device for holding and extruding the contents of a collapsible tube, the combination of a base having a collapsible tube securing means at its lower end and guideways extending vertically along its sides, a carriage mounted to move freely between the guideways upon said base, an anvil member mounted to move with said carriage and pivot about an axis extending transverse to the line of movement of said carriage, spring means operating to bias said anvil member about its pivotal axis and into contact with a collapsible tube secured upon said base portion, and a lever having an eccentric cam-like hub portion pivotally mounted in spaced relation with said anvil and operating about an axis parallel to the pivotal axis of said anvil member adapted when operated to move its cam-like hub portion into pressure producing engagement with the side of a collapsible tube and by pressure exerted through said tube cause said anvil member to pivot in an opposite direction and produce a kneading action upon the collapsible tube.

2. In a device for holding and extruding the contents of a collapsible tube, the combination of an elongated base having a collapsible tube securing means at one end and guideways extending along its sides, a carriage mounted to

move freely between the guideways upon said base, an anvil member pivotally mounted upon said carriage and having a cylindrical portion adapted and arranged to rock about an axis extending transverse to the line of movement of said carriage, spring means operating about the pivotal axis of said anvil member for biasing it into contact with a collapsible tube held upon said base by said securing means, and a cam-like member also pivotally mounted upon said carriage in spaced relation with and operating about an axis parallel to the pivotal axis of said anvil member, and an operating lever extending outwardly from said cam-like member adapted when pressure is exerted thereupon to move said cam-like member against the adjacent side of a collapsible tube and cause said anvil member to rock in an opposite direction with a kneading action upon the collapsible tube.

3. A support for holding and extruding the contents of a collapsible tube, comprising a base portion having collapsible tube holding means at its lower end and vertically extending guideways along its sides, a frame slidably mounted upon the guideways of said base portion, a pivotally mounted cylindrical anvil against which one side of a collapsible tube may be placed, said anvil being mounted to pivot about an axis eccentric to its cylindrical surface and yield when pressure is exerted thereupon, and a cam-like member having an operating lever pivotally mounted upon said frame opposite said semi-cylindrical anvil adapted when operated to exert a downward pressure upon the opposite side of the collapsible tube and extrude its contents as said anvil pivots in an upward direction.

4. A support for holding and extruding the contents of a collapsible tube, comprising a base portion adapted to be secured upon a wall, a collapsible tube holding means at the lower end of said base portion for gripping the neck of a collapsible tube, vertically extending guideways extending along the sides of said base portion, a frame slidably mounted to move along guideways of said base portion as the contents of a collapsible tube are extruded therefrom, a semi-cylindrical anvil against which one side of a collapsible tube will be positioned by said holding means, said semi-cylindrical anvil being pivotally mounted eccentrically to yield in an upward direction when pressure is exerted thereupon through said tube, and a cam-like member pivotally mounted upon said frame opposite said yielding anvil forming member having an operating lever adapted to exert a downwardly applied pressure upon the opposite side of a collapsible tube when said lever is operated, whereby the combined movements of said anvil and said cam-like member will produce a kneading action at the closed end of the collapsible tube disposed therebetween.
